UNITED STATES PATENT OFFICE.

ROBERT J. HODGE, OF WEST HAVEN, CONNECTICUT, ASSIGNOR TO THE AMERICAN BUCKLE CO., OF WEST HAVEN, CONNECTICUT, A CORPORATION.

WIRE-CUTTER.

1,317,444.

Specification of Letters Patent. Patented Sept. 30, 1919.

Application filed June 27, 1919. Serial No. 307,095.

To all whom it may concern:

Be it known that I, ROBERT J. HODGE, a citizen of the United States, residing at West Haven, in the county of New Haven and State of Connecticut, have invented a new and useful Improvement in Wire-Cutters; and I do hereby declare the following, when taken in connection with the accompanying drawings and the characters of reference marked thereon, to be a full, clear, and exact description of the same, and which said drawings constitute part of this application, and represent, in—

Figure 1 a top or plan view of a wire cutter constructed in accordance with my invention.

Fig. 2 a side view of the same.

Fig. 3 an end view thereof.

Fig. 4 a plan view of the bed-block with the top removed.

Fig. 5 a side view of the same.

Fig. 6 an end view.

Fig. 7 a plan view of the top plate detached.

Fig. 8 an end view of the same.

Fig. 9 a plan view of the plunger detached.

Fig. 10 a side view of the same.

Fig. 11 an end view of the same.

Fig. 12 a side view of the stripper, detached.

Fig. 13 an end view of the same.

Fig. 14 a side view of the stripper spring detached.

Fig. 15 an end view of the same.

Fig. 16 a side view showing a portion of the wire with two cuts producing a piece with reversely beveled ends.

Fig. 17 a plan view of the same.

Fig. 18 shows one of the chips removed.

Fig. 19 is a plan view of a buckle having its double pointed wire lever cut in accordance with my invention.

Fig. 20 a side view of the same.

Fig. 21 a side view of the tongue, detached.

This invention relates to an improvement in wire cutters particularly adapted for use in connection with wire bending machines.

50 In some cases, and particularly for buckles for overalls and suspenders in which the lever includes two prongs, in the usual manner of cutting the wire one of the prongs is beveled in one direction, and the other

prong in the opposite direction, necessitating a separate operation to form the points so that they will have the same appearance.

The object of this invention is to so cut the wire as it is fed into the machine that the ends of the cut pieces be beveled in opposite directions; and the invention consists in the construction hereinafter described and particularly recited in the claims.

In carrying out my invention I employ a bed-block 25 which is secured to the machine frame of an ordinary wire-bending machine in position between the straightening mechanism, if any is employed, and the bending mechanism of whatever form it may be. Preferably the under face is 65 formed with a longitudinal rib 26 to fit in a groove formed for it in the bed of the machine, whereby the device may be firmly held in proper alinement. Secured to the block 25 is a top plate 27 which is secured 70 thereto by bolts 28 and 29, being also held in place by a dowel pin 30 depending from its under face and entering a hole 31 formed for it in the bed block. The top plate 27 is also formed with an alinement rib 32 75 entering a groove 33 formed for it in the upper face of the bed-block. The top plate is formed at one side with a cutter arm 34 the under or cutting faces 35 and 36 of which are reversely beveled and sharpened 80 so as to form a flattened V shaped cutter the point 37 of which extends down closely to the upper face of the bed block 25. The bed-block is formed with a channel 38 in which 85 a horizontal movable plunger 39 is arranged, this plunger being adapted to be moved back and forth by an arm 40 of a swinging block 41 which may be operated by any suitable means so as to move the plunger back and forth. The plunger is 90 formed in its upper face with a flattened V-shaped channel, the faces 42 and 43 of which conform with the edges 35 and 36 of the cutter. Near the end of the plunger is a transverse groove 44 to receive the wire 95 45 which is to be fed to the bending mechanism. As herein shown, the groove is formed by the application to the end of the plunger of a block 46 held in place by a screw 47 and dowel pin 48. The plunger is 100 held in position by the edge 49 of the top plate overlapping the edge of the groove 48, thus forming a partly housed guideway 105

for the plunger. The plunger is placed in the groove 38 and the top plate 27 secured in place. It may here be noted that the plates 25 and 27 are formed with alined notches 50 and 51 through which a bolt may extend for further connecting the device to the machine bed.

The wire to be cut enters a wide groove 52 formed for it in the bed block and passes through the notch 44 in the plunger by which it is advanced to the cutting edges 35 and 36 which removes a wedge shaped chip 53 as shown in Fig. 18, thus cutting wire and forming one end 54 with a bevel in one direction and the end 55 with a bevel in the opposite direction, the groove 52 being of sufficient width to permit the wire to be carried past or sufficiently across the cutters 35 and 36 to get a clean cut. When the plunger retires, the chip 53 is removed from the upper face thereof by means of a stripper 56 pivoted on a screw 57 and normally pressed downward across the plunger by means of a spring 58 which is secured to the top plate 27 by means of screws 59. The wire is then fed forward to a predetermined extent and another chip removed, thus forming a length of wire 60 with reversely beveled ends 54 and 55 the length of wire being then fed to a forming mechanism; and if it is for a buckle the ends 61 will be inclined in the same direction and present

their beveled surfaces against the face 62 of a buckle frame 63 of usual construction.

I claim:—

1. A wire cutter comprising a bed-block formed with a plunger groove, a top plate secured to the bed-block and extending over the plunger groove, a plunger movable in said plunger groove, said top plate formed with a wedge-shaped cutter, the plunger formed with a corresponding groove and adapted to force a piece of wire across said cutter, and means for moving said plunger. 40

2. A wire cutter comprising a bed-block 45 formed with a plunger groove, a top plate secured to said bed-block and projecting over said plunger groove, a plunger movable in said plunger groove, means for moving said plunger, said top plate formed with 50 a wedge-shaped cutter, the plunger formed with a groove and adapted to support a wire and move it across said cutter, a stripper secured to the top plate and resting upon the plunger, and a spring normally pressing 55 the stripper against said plunger.

In testimony whereof, I have signed this specification in the presence of two subscribing witnesses.

ROBERT J. HODGE.
